UNITED STATES PATENT OFFICE.

WILLIAM A. BRYANT, OF GLEN RIDGE, NEW JERSEY.

DESIGN FOR A FINGER-RING.

SPECIFICATION forming part of Design No. 20,058, dated July 29, 1890.

Application filed July 1, 1890. Serial No. 357,421. Term of patent 7 years.

To all whom it may concern:

Be it known that I, WILLIAM A. BRYANT, of Glen Ridge, in the county of Essex and State of New Jersey, have originated and produced a new and original Design for Finger-Rings, of which the following is a specification.

My design consists in a finger-ring whose shank or body is made one half of a twisted configuration and the other half different.

In the accompanying drawings, Figure 1 is a side view of a ring embodying the design. Fig. 2 is a view of the same looking toward the head.

Similar letters of reference designate corresponding parts in both figures.

It will be seen that one half a' of the shank or body of the ring is made of a twisted con-

figuration and the other half a^2 plain. These two halves at one end meet under the head b 20 and at the other end at an opposite point. The head b may be made as desired, as it forms no part of the present design. It is here shown as made in the shape of a horse-shoe set obliquely and surrounding a stone. 25

What I claim as my design, and desire to secure by Letters Patent, is—

A design for a ring, consisting of a shank or body having one half made of a twisted configuration and the other of a different or 30 contrasting configuration, substantially as shown and described.

WILLIAM A. BRYANT.
